CALVERT B. COTTRELL, 3D, OF WESTERLY, RHODE ISLAND, ASSIGNOR TO C. B. COTTRELL & SONS COMPANY, OF WESTERLY, RHODE ISLAND, A CORPORATION OF DELAWARE

BED AND CYLINDER PRINTING PRESS

Application filed June 30, 1931. Serial No. 547,837.

My invention is applicable to the type of bed and cylinder presses disclosed in my co-pending application filed April 28th, 1931, Serial No. 533,426, in which the form rollers 5 of the inking mechanism are driven continuously in one direction only and in which the form and form rollers are separated during the non-inking stroke and are brought into coaction during the inking stroke. In 10 the form illustrated herein and in the said application the form is moved out of the path of the form rollers on the non-printing stroke of the bed and into the path of the said form rollers on the printing stroke of the bed.

15 In bed and cylinder printing presses of the type disclosed herein where a motor, which is independent of the bed drive, forms a part of the inking mechanism and is used for driving the form rollers in one direction only, it is difficult to synchronize the surface speeds 20 of the form and form rollers during the application of ink to the form.

The object of my invention, therefore, is to provide means controlled by the bed for 25 bringing the surface speed of the form rollers to the surface speed of the form when in contact therewith during the inking stroke of the bed so as to ensure a perfect rolling contact between the form rollers and form, 30 and thus cause the even application of the ink to the form.

My invention more particularly comprises 35 a clutch mechanism, as for instance one-way or slip clutches on the form rollers whereby when the form is brought into contact with the rollers the clutches will slip sufficiently to permit the rollers to speed up to the surface speed of the form during the inking stroke 40 of the bed.

A practical embodiment of my invention is represented in the accompanying drawings in which:

Fig. 1 represents a side elevation of my 45 improved bed and cylinder printing press, the parts being shown in the positions they assume when the bed has proceeded part way on its printing and inking stroke;

Fig. 2 represents a similar view with the 50 parts in the positions they assume when the

bed has proceeded part way on its non-printing and non-inking stroke;

Fig. 3 represents a detail vertical longitudinal section taken in the plane of the line 55 III—III of Fig. 4;

Fig. 4 represents a detail plan view;

Fig. 5 represents a detail vertical longitudinal section taken in the plane of the line 60 V—V of Fig. 4;

Fig. 6 represents a detail horizontal section taken in the plane of the line VI—VI of Fig. 5;

Fig. 7 represents a detail side view of the reciprocating form bed, the form member in 65 this view being shown raised into position to bring the form into contact with the form rollers of the inking mechanism on the forward or printing stroke of the bed;

Fig. 8 represents a similar view with the 70 form member shown lowered into position to bring the form out of contact with the form rollers on the reverse or non-printing stroke of the bed;

Fig. 9 represents a transverse vertical section through the bed taken in the plane of the 75 line IX—IX of Fig. 7, looking in the direction of the arrows;

Fig. 10 represents a bottom plan view of the upper or form member of the bed;

Fig. 11 represents a top plan view of the 80 lower or base member of the bed;

Fig. 12 represents an end view of the form member; and

Fig. 13 represents an end view of the base member.

The main frame of the printing press is denoted by 1. The form bed which is fitted to reciprocate in the main frame is shown as comprising an upper or form member 2 and a lower or base member 3, the upper member serving to carry the printing form 4 and having a limited diagonal sliding movement on the lower or base member 3 longitudinally of the press; in the present instance by providing the upper or form member 2 with an inclined bottom surface and the lower or base member 3 with a coacting reversely inclined top surface.

A lost motion connection is provided between the form and base members. The base 100

member 3 is provided with a front cross rib 3* and a rear cross rib 3** which serve to limit the forward and upwardly and the rearward and downward sliding movements respectively of the form member on the base member. The form bed may be reciprocated by any suitable means, that shown herein comprising an electric motor 5 which drives motive fluid pumps 6 and 7 having suitable motive fluid connections with their respective longitudinally disposed fixedly mounted cylinders 8 and 9 below the form bed. This piston 10 which slides in the cylinder 8 is connected to an arm 11 depending from the front end of the form member 2 of the bed for moving the bed rearwardly and the piston 12 which slides in the cylinder 9 is connected to an arm 13 depending from the rear end of the form member 2 for moving the bed forwardly. As this bed reciprocating means forms no part of the present invention it will not be more specifically described herein, it being understood that suitable motive fluid connections are provided to ensure the reciprocation of the bed by the pumps 5 and 6.

The inking mechanism is shown as comprising an ink fountain 14, distributing rollers 15, form rollers 16 and an electric motor 17, which motor is independent of the bed reciprocating means and drives both the distributing rollers 15 and form rollers 16 in one direction only, to ensure an even application of the ink to the form 4 on the printing and inking stroke of the bed. The distributing rollers 15 are positively driven from the motor gear 18 through the gears 19, 20, 21, 22. The form roller gears 23, in the present instance four gears, are positively driven from the two distributing roller gears 24 and each form roller gear 23 has a one-way or slip clutch driving connection 25 with its form roller 16 so that when the form 4 comes into contact with its form rollers 16 on the printing and inking stroke the form rollers 16 are caused to travel at the surface speed of the form. In the present instance the form rollers are driven by the motor 17 at a slightly slower speed than the surface speed of the form and when the form comes into contact with the form rollers the surface speed of the form rollers is increased to the surface speed of the form.

The oscillating impression cylinder 26 is fixedly mounted in the main frame 1 and it is geared at all times to the reciprocating bed through the usual gear and rack connection 27, 28, the rack being attached to the form member 2 of the bed so that the form and cylinder are kept in perfect register in the operation of the press. This impression cylinder may be provided with a set of tumbler actuated grippers 29, operable through the oscillation of the cylinder, to take the sheets from the feed table 30 and deliver them

tail end first to the stripping fingers 31 of the delivery mechanism 32.

In operation: As the form bed starts on its printing and inking stroke the form member will be raised by its diagonally upward sliding movement on the base member due to the action of the piston 10 in the cylinder 8, so that as the bed proceeds to the end of its stroke the form will first be brought into contact with the sheet carried by the impression cylinder and then into contact with the form rollers 16. During the time that the form is in contact with these form rollers they will be under the control of the form and will be rotated at the surface speed thereof. As the form bed starts on its non-printing and non-inking stroke the form member is lowered by its diagonally downward sliding movement on the base member due to the action of the piston 12 in the cylinder 9 so that the form will fail to contact with the form rollers of the inking mechanism during this stroke of the bed, and the form rollers will thus be under the control of the motor 17 of the inking mechanism.

From the above description it will be seen that the form rollers are driven continuously in one direction only on the printing stroke by the bed, and on the non-printing stroke by the motor, simple and effective means being provided for causing the form rollers to travel at the surface speed of the form when in contact therewith.

It is evident that various changes may be resorted to in the construction, form and arrangement of the several parts without departing from the spirit and scope of my invention, and hence I do not intend to be limited to the particular embodiment herein shown and described, but

What I claim is:—

1. In a bed and cylinder printing press, a reciprocating form bed, an inking mechanism therefor including form rollers driven continuously in one direction only, and means controlled by the bed for causing the form rollers to travel at the surface speed of the form when in contact therewith.

2. In a bed and cylinder printing press, a reciprocating form bed, an inking mechanism therefor including form rollers driven continuously in one direction only, means controlled by the bed for causing the form rollers to travel at the surface speed of the form when in contact therewith, and means to cause the separation of the form and form rollers on the non-inking stroke of the bed.

3. In a bed and cylinder printing press, a reciprocating form bed, an inking mechanism therefor including form rollers driven continuously in one direction only, means controlled by the bed for causing the form rollers to travel at the surface speed of the form when in contact therewith, and means to move the form out of the path of the form

rollers on the non-inking stroke of the bed.

4. In a bed and cylinder printing press, a reciprocating form bed, an inking mechanism therefor including form rollers and a motor for driving them in one direction only, and means controlled by the bed for causing the form rollers to travel at the surface speed of the form when in contact therewith.

5. In a bed and cylinder printing press,
10 a reciprocating form bed, an inking mechanism therefor including form rollers and a motor for driving them in one direction only, means controlled by the bed for causing the form rollers to travel at the surface speed of
15 the form when in contact therewith, and means to cause the separation of the form and form rollers on the non-inking stroke of the bed.

6. In a bed and cylinder printing press,
20 a reciprocating form bed, an inking mechanism therefor including form rollers and a motor for driving them in one direction only, means controlled by the bed for causing the form rollers to travel at the surface speed
25 of the form when in contact therewith, and means to move the form out of the path of the form rollers on the non-inking stroke of the bed.

7. In a bed and cylinder printing press,
30 a reciprocating form bed, an inking mechanism therefor including form rollers driven continuously in one direction only, and a slip clutch mechanism controlled by the bed for causing the form rollers to travel at the sur-
35 face speed of the form when in contact therewith.

40 8. In a bed and cylinder printing press, a reciprocating form bed, an inking mechanism therefor including form rollers driven continuously in one direction only, a slip clutch mechanism controlled by the bed for causing the form rollers to travel at the surface speed of the form when in contact therewith, and means to cause the separation of the form and form rollers on the non-inking stroke of the bed.

9. In a bed and cylinder printing press, a reciprocating form bed, an inking mechanism therefor including form rollers driven continuously in one direction only, a slip clutch mechanism controlled by the bed for causing the form rollers to travel at the surface speed of the form when in contact therewith, and means to move the form out of the path of the form rollers on the non-inking stroke of the bed.

10. In a bed and cylinder printing press, a reciprocating form bed, an inking mechanism therefor including form rollers and a motor for driving them in one direction only, and a slip clutch mechanism controlled by the bed for causing the form rollers to travel at the surface speed of the form when in contact therewith.

65 11. In a bed and cylinder printing press,

a reciprocating form bed, an inking mechanism therefor including form rollers and a motor for driving them in one direction only, a slip clutch mechanism controlled by the bed for causing the form rollers to travel at the surface speed of the form when in contact therewith, and means to cause the separation of the form and form rollers on the non-inking stroke of the bed. 70

12. In a bed and cylinder printing press, 75
a reciprocating form bed, an inking mechanism therefor including form rollers and a motor for driving them in one direction only, 80
a slip clutch mechanism controlled by the bed for causing the form rollers to travel at the surface speed of the form when in contact therewith, and means to move the form out of the path of the form rollers on the non-inking stroke of the bed.

13. In a bed and cylinder printing press, a reciprocating form bed, an inking mechanism therefor including form rollers driven continuously in one direction only, and slip clutches on the form rollers, controlled by the bed for causing the form rollers to travel at the surface speed of the form when in contact therewith. 85 90

14. In a bed and cylinder printing press, a reciprocating form bed, an inking mechanism therefor including form rollers driven continuously in one direction only, slip clutches on the form rollers, controlled by the bed for causing the form rollers to travel at the surface speed of the form when in contact therewith, and means to cause the separation of the form and form rollers on the non-inking stroke of the bed. 95 100

15. In a bed and cylinder printing press, a reciprocating form bed, an inking mechanism therefor including form rollers driven continuously in one direction only, slip clutches on the form rollers, controlled by the bed for causing the form rollers to travel at the surface speed of the form when in contact therewith, and means to move the form out of the path of the form rollers on the non-inking stroke of the bed. 103 110

16. In a bed and cylinder printing press, a reciprocating form bed, an inking mechanism therefor including form rollers and a motor for driving them in one direction only, and slip clutches on the form rollers controlled by the bed for causing the form rollers to travel at the surface speed of the form when in contact therewith. 113 120

17. In a bed and cylinder printing press, a reciprocating form bed, an inking mechanism therefor including form rollers and a motor for driving them in one direction only, slip clutches on the form rollers controlled by the bed for causing the form rollers to travel at the surface speed of the form when in contact therewith, and means to cause the separation of the form and form rollers on the non-inking stroke of the bed. 130

18. In a bed and cylinder printing press, a reciprocating form bed, an inking mechanism therefor including form rollers and a motor for driving them in one direction only, 5 slip clutches on the form rollers controlled by the bed for causing the form rollers to travel at the surface speed of the form when in contact therewith, and means to move the form out of the path of the form rollers on the non-inking stroke of the bed.

10 In testimony, that I claim the foregoing as my invention, I have signed my name this 25th day of June, 1931.

CALVERT B. COTTRELL, 3RD.
